OTTO PEDERSEN Inventor

By Richard B. Diven

Attorney

UNITED STATES PATENT OFFICE.

OTTO PEDERSEN, OF BROOKLYN, NEW YORK.

PIPE-WRENCH.

1,325,906.

Specification of Letters Patent. Patented Dec. 23, 1919.

Application filed September 10, 1919. Serial No. 322,812.

To all whom it may concern:

Be it known that I, OTTO PEDERSEN, a citizen of the United States, residing at Brooklyn, in the county of Kings and State of New York, have invented certain new and useful Improvements in Pipe-Wrenches, of which the following is a specification.

This invention relates to wrenches of the alligator type, and the object is to provide a simple and effective wrench so constructed that when it is placed on a pipe or rod and pressure exerted on the handle in one direction, the jaws will be closed and the pipe firmly gripped and held.

Another object is to provide a wrench of this character with a sliding and a pivoted jaw connected to coöperate to grip and reliably retain a pipe or other object without any adjustment being necessary, a manipulation of the handle operating to actuate these jaws.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation with parts broken out of the wrench constituting this invention with a pipe shown gripped between the jaws thereof, said pipe being in section.

Fig. 2 is a longitudinal detail section taken on the line 2—2 of Fig. 1,

Fig. 3 is a similar view taken on the line 3—3 of Fig. 1, and

Fig. 4 is a transverse section taken on the line 4—4 of Fig. 1.

In the embodiment illustrated, a handle 1 is shown having an integral arm 2 extending obliquely outward from one end thereof, and which has the usual shape of an alligator wrench jaw. This arm or jaw 2 is provided along the side edges of its inner face with laterally extending flanges 3. A sliding toothed member 5 has inturned flanges 6 on its side edges adapted to extend under the flanges 3 of the arm 2 as is shown clearly in Fig. 4, whereby the member 5 is held in sliding relation to said arm. The teeth 4 of this member are inclined out-

wardly as shown in Fig. 1 and are designed to coöperate with inwardly inclined teeth on a pivoted jaw 10.

A recess 7 is formed at the inner end or 60 base of arm 2 on its inner face and a short arm 8 extends obliquely outward from the handle in a direction opposite to the arm 2 and is designed to support the pivoted jaw 10 and to operate as a stop for limiting its outward movement. This arm 8 has an apertured lug 9 extending from its inner edge or face, and on which jaw 10 is pivoted as shown at 11. Shoulders 12 are formed on either side of the lug 9 so that the rear 70 curved edge 13 of jaw 10 will abut thereagainst and limit the opening movement of said jaw.

The jaw 10 has a substantially right- 75 angular finger 14 extending from its pivoted end edgewise toward the arm 2, the end of said finger being curved to operate in the recess 7. This finger 14 is connected by a link 15 with the inner end of the sliding jaw 5 so that when said sliding jaw 5 80 reciprocates on arm 2 it will actuate the pivoted jaw 10, the inward movement of said sliding jaw causing the pivoted jaw to close and the outward movement thereof operating to open the pivoted jaw. It will thus 85 be seen that when the sliding jaw member 5 is engaged with a pipe P or other object to be gripped, and the handle 1 moved toward the left, jaw 5 will move inwardly and thereby close jaw 10 into gripping engagement with the pipe, and the teeth of these coöoperating jaws will securely hold the pipe relatively to the wrench.

From the above description it will be obvious that this wrench, while very cheap to 90 manufacture, is strong and effective in operation, and has few parts to get out of order or to be broken.

From the foregoing description, taken in connection with the accompanying drawings, the advantage of the construction and of the method of operation will be readily apparent to those skilled in the art to which the invention appertains and while I have described the principle of operation of the 105 invention together with the device which I now consider to be the best embodiment thereof, I desire to have it understood that the device shown is merely illustrative and that such changes may be made as are within 110 the scope of the claimed invention.

Having thus fully described my invention,

what I claim as new and desire to secure by Letters Patent, is:—

- 5 1. A wrench of the class described comprising a handle with a slidable and a pivoted jaw mounted thereon, a link connection between said jaws whereby the inward movement of the sliding jaw will operate to close the pivoted jaw and its outward movement to open it.
- 10 2. A wrench of the class described comprising a handle with a slidable and a pivoted jaw mounted thereon, a link pivotally connecting the inner ends of said jaws whereby the movement of the sliding jaw will operate to actuate the pivoted jaw.
- 15 3. A wrench of the class described comprising a handle with a rigid arm extending obliquely from one end, a toothed jaw mounted to slide on the inner face of said
- 20 20 fixed arm, a jaw pivoted at its inner end adjacent the base of said arm and having a finger extending laterally from said pivot, and a link connecting the free end of said

finger with the inner end of said sliding jaw.

- 25 4. A wrench of the class described comprising a handle with a rigid arm extending obliquely from one end with a recess at the base of its inner face, and a short arm extending obliquely in a direction opposite to said first mentioned arm, a toothed jaw mounted to slide on the inner face of said first-mentioned arm, a jaw pivoted at its inner end on said short arm with a finger extending laterally from said pivot in edge-wise direction from said jaw, a link connecting the free end of said finger with the inner end of said sliding jaw, said short arm having means for limiting the opening movement of the pivoted jaw.

In testimony whereof I affix my signature in presence of two witnesses.

OTTO PEDERSEN.
